UNITED STATES PATENT OFFICE.

FREDERICK W. CHESSON, OF WATERBURY, CONNECTICUT, ASSIGNOR TO
THE AMERICAN RING COMPANY, OF SAME PLACE.

DESIGN FOR A METAL MOUNT.

SPECIFICATION forming part of Design No. 27,397, dated July 20, 1897.

Application filed December 26, 1896. Serial No. 617,116. Term of patent 7 years.

To all whom it may concern:

Be it known that I, FREDERICK W. CHES-
SON, a citizen of the United States, residing
at Waterbury, in the county of New Haven
5 and State of Connecticut, have invented and
produced a new and original Design for Metal
Mounts, of which the following is a specifica-
tion, reference being had to the accompanying
drawings, in which—

10 Figure 1 is an elevation, and Fig. 2 a plan,
of my design.

The general configuration of the metal
mount is round; and the leading features of
my design consist in the flattened spheroidal
15 body, the adjacent convex bead, the cove, the

curved contracted portion, and contracted
end, as shown.

The flattened spheroidal body is shown at *a*,
the convex beads at *b b'*, the coves at *c c'*, the
curved contracted portions at *d d'*, and the 20
contracted ends at *e e'*.

What I claim is—

The design for a metal mount, substantially
as shown and described.

Signed by me this 17th day of December, 25
A. D. 1896.

F. W. CHESSON.
